DESCRIPTION

U.S. PATENT DOCUMENTS

FIG. 1 is a perspective view of a nozzle showing my new design;

3,150,829 A *	9/1964	Specht et al.	.....	239/107
3,207,444 A	9/1965	Kelly et al.		
4,469,279 A *	9/1984	Allenbaugh, Jr.	.....	239/453
4,470,549 A	9/1984	McMillan et al.		
4,899,940 A	2/1990	Leaver		
4,903,897 A	2/1990	Hayes		
D325,620 S	4/1992	Heren		
D338,706 S	8/1993	Wang		
D340,762 S	10/1993	Wang		
D355,952 S	2/1995	Wang		
D355,953 S	2/1995	Wang		
D359,101 S	6/1995	Kuo		
D372,297 S	7/1996	Wang		
D373,814 S	9/1996	Wang		
D384,398 S	9/1997	Wang		
D385,948 S	11/1997	Guo		

FIG. 2 is a left side elevational view showing the design for the nozzle of FIG. 1;

FIG. 3 is a right side elevational view showing the design for the nozzle of FIG. 1;

FIG. 4 is a top elevational view showing the design for the nozzle of FIG. 1;

FIG. 5 is a bottom elevational view showing the design for the nozzle of FIG. 1;

FIG. 6 is a front elevational view showing the design for the nozzle of FIG. 1; and,

FIG. 7 is a rear elevational view showing the design for the nozzle of FIG. 1.

The broken line showing of portions of the nozzle is included for illustrative purposes only and forms no part of the claimed design.
